CLAIM

The ornamental design for a footwear outsole, as shown and described.

DESCRIPTION

FIG. 1 is a bottom plan view of a footwear outsole showing our new design;

FIG. 2 is an enlarged cross-sectional view taken along line 2—2 of FIG. 1;

FIG. 3 is a right side elevational view of FIG. 1;

FIG. 4 is a top plan view of FIG. 1;

FIG. 5 is a left side elevational view of FIG. 1;

FIG. 6 is a front elevational view of FIG. 1; and,

FIG. 7 is a rear elevational view of FIG. 1.

The broken lines showing the rear portion of the outsole in FIGS. 1, 3, 4 and 7 are for illustrative purposes only and form no part of the claimed design. The long and short broken lines around the perimeter of the inner sole in FIGS. 2, 4 and 7 show the boundary of the claimed design, and neither the broken lines nor the area lying within them form part of the claim. The broken lines shown in the cross-sectional surface of FIG. 2 and in that surface's boundary with the inner sole are provided only to indicate that the cross-sectional surface and inner sole boundary form no part of the claimed design.
